UNITED STATES PATENT OFFICE.

MACKINTOSH HUTCHINSON, OF TORONTO, ONTARIO, CANADA.

ASH-SIFTER.

1,383,812.

Specification of Letters Patent.

Patented July 5, 1921.

Application filed January 2, 1919. Serial No. 269,299.

To all whom it may concern:

Be it known that I, MACKINTOSH HUTCHINSON, a subject of the King of Great Britain, residing at Toronto, in the Province of Ontario and Dominion of Canada, have invented certain new and useful Improvements in Ash-Sifters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to ash sifters although it may be used for sifting or screening other materials.

It has for its object to provide a base for the sifter or screen which may be fitted to receptacles or cans of stock or standard size designed to receive the finer screenings or particles and which will support the screen or sifter in a stable manner and permit its easy rotation and practically prevent the escape of fine dust during the operation of screening.

To the accomplishment of the foregoing and such other objects as may hereinafter appear, the invention consists in the features hereinafter described and then sought to be clearly defined by the claims, reference being had to the accompanying drawing forming a part hereof, and in which—

Figure 1 is a plan view of the screen base; Fig. 2 is a vertical section through a screen, its base, and the receptacle or case receiving the finer sifted particles or screenings;

Fig. 3 is a detail sectional view of a modified form of base, showing its relation to the screen and to the receiving can.

In the drawing the numeral 1 designates a demountable rim of any suitable form and material provided at its inner circumference with depending lips 2 adapted to fit within the upper end of a can or receptacle 3 designed to receive the siftings or screenings separated from the larger particles of material by the screen 4 and its container 5. The rim 1 is surmounted by a ring or annulus 6 of any desired material and suitably secured to the demountable rim and which carries a number of rollers 7 set within recesses 8 formed at the inner circumference of the ring and journaled on bolts or screws

9. The bolts or screws 9 also hold in place an annular ring flange 10 which serves to brace the rollers and to serve as washers for the same, and in the preferred form, illustrated in Figs. 1 and 2, extends upwardly and serves as a dust guard tending to prevent the escape of dust between the receiving receptacle 3 and screen container 5 as well as a guide for the container 5 in revolving the same over the rollers 7. To effect a close joint between the ring flange 10 and the inner face of the annulus 6 so that there will be no open spaces at such junction, the ring flange 10 may be further secured or fastened by screws or pins 11. The container 5 for the material to be sifted or screened has at its lower edge an inwardly extending flange 12 between which and the wall of the container 75 the edge of the screen 4 is secured, the upper portion of the flange being turned inwardly to form a lip 13 which constitutes a seat for the screen as illustrated in Fig. 2, said lip resting on the top edge of the guard 80 and guide flange 10, and the lower folded edge of the container resting on the rollers 7 of the demountable rim. Under the construction described, the demountable rim is readily fitted to cans or receptacles of stock 85 or standard size and held by the lips 2 against sliding movement thereon; the container 5 is easily revoluble on the rollers 7; the dust guard and guide flange will tend to prevent the escape of dust and at the same time serve as a guide for the container and also hold the rollers within the recesses formed for them; and the rim can be readily demounted and replaced on the same or other receptacle as occasion may require. 95 The rim with its annulus or ring and the rollers and dust and guide flange constitute a unitary structure which is light and strong and separable from the screen container and receiving receptacle and adapted for use 100 with different containers and receptacles and gives stability to the container and receptacle.

Instead of having the flange 10 extend above the annulus or ring 6 as in the preferred construction it may terminate below the top of the ring as illustrated at 10¹ in Fig. 3 of the drawing, and in such modified form the rollers may lie below the top face of the annulus or ring 6 and project partially into a rabbet 14 in the ring, as shown in Fig. 3, and in such form the lower edge

2 / of the screen container may be beaded and will bear against a shoulder of the annulus or ring, as indicated in Fig. 3, so as to be held in place in its rotation. The demountable rim, however, together with its annulus or ring, and the rollers, and flange for holding the rollers in their recesses, in this modified form, are, in the elements specified and their functions substantially the same as in 10 the preferred form of the device.

Having described my invention and set forth its merits, what I claim is:

1. A sifter comprising a demountable rim adapted to rest upon a receptacle, rollers and 15 bearings therefor attached to said rim, and a container provided with a sieve, the lower wall of the container extending below the sieve to constitute a flange to rest upon the periphery of the rollers of the demountable 20 rim, said container and its sieve being separable and removable from the demountable rim without removal of the rim and its rollers from the receptacle.

2. A sifter comprising a demountable rim 25 adapted to rest upon a receptacle, rollers supported upon the rim, a container provided with a sieve, the lower wall of the container extending below the sieve to con-

stitute a downwardly extending flange to rest upon the periphery of the rollers of the 30 demountable rim, and a flange connected with the demountable rim and extending above the periphery of the rollers and lying inside of the depending flange of the container to form a dust guard inside of the 35 depending flange of the container and a guide for the container.

3. In a sifter comprising a container provided with a screen, and a receptacle to receive the screenings; a demountable rim 40 to rest upon the receptacle and provided with an annulus or ring formed with roller recesses, rollers journaled in the recesses, a flange at the inner circumference of the annulus or ring and projected to extend into 45 the container to form a dust guard and guide; the container having an inwardly extending lip extending over the upper edge of the dust guard and guide, substantially as described.

In testimony whereof I affix my signature in presence of two witnesses.

MACKINTOSH HUTCHINSON.
